UNITED STATES PATENT OFFICE.

HENRY D. RAHLING, OF EAST AURORA, NEW YORK, ASSIGNOR TO STEEL DRUM ACCESSORIES CORPORATION, OF BUFFALO, NEW YORK, A CORPORATION OF NEW YORK.

BIB OR FAUCET.

Application filed May 17, 1924. Serial No. 714,020.

This invention relates to an improved bib or faucet particularly adapted for use with containers from which liquid is required to be drawn from time to time.

5 The object of the invention is to provide a bib or faucet which will be relatively small in size and hence economical to manufacture, while permitting the flow of liquid at the same rate as with the larger faucets 10 that are commonly employed, which will effectively prevent leakage when closed, and which may be operated with facility.

The invention consists generally in novel details of structure and combination which 15 will be set forth at length as the description proceeds.

Embodiments of the invention are illustrated in the accompanying drawings, wherein:

20 Figure 1 is a longitudinal sectional view of a bib or faucet embodying my improvements.

Figure 2 is a cross sectional view on the line 2—2 of Figure 1.

25 Figure 3 is an end elevation of the valve element.

Figure 4 is a side elevation of the valve element.

Figure 5 is a detail sectional view showing 30 more particularly the arrangement of a ball employed as a guide and detent element.

Figure 6 is a similar view showing a modified construction wherein a pin is employed as a guide and detent element.

35 Figure 7 is a fragmentary longitudinal sectional view of a further modified construction.

Figure 8 is a cross section on the line 8—8 of Figure 7.

40 Figure 9 is an elevation of the guide and detent embodied in the construction of Figure 7.

Figure 10 is an end elevation showing a further modified construction.

45 Figure 11 is a fragmentary side elevation thereof.

Referring to Figures 1 to 5:

The faucet comprises a tubular body 1 adapted by means of a threaded extension 2 50 to be fitted to a wall of the liquid container and having adjacent its end remote from the extension 2 a discharge spout 3 which extends at an angle to the body 1. At its outer end the body 1 is closed by a valve plug 4 55 which is inserted co-axially in said body and

is rotatably mounted. The plug 4 extends across the passage of the spout 3 and is preferably of slightly tapering form, the adjacent part of the body 1 being conformably tapering whereby the plug 4 has a snug fit 60 in said body. The plug 4 is wholly cut away on one side as shown at 5 to provide a large clearance by which communication may be established between the interior of the body 1 and the passage of the spout 3. In its closed position the solid portion of the plug 4 extends across the spout 3 and provides a complete closure therefor. In the fully open position of said plug the wall of the cut-away portion squarely overhangs the spout 3, as shown by broken lines in Figure 1, 70 whereby an unobstructed passage of relatively large volume is afforded through which liquid may flow freely from the body 1 to the spout 3.

75 The plug 4 is formed beyond the clearance or cutaway portion 5 with a bearing portion 6 of annular cross section which carries a suitable finger piece 7 by which the plug may be turned.

80 The plug is held against endwise displacement from the body 1 by a key 8 which is preferably in the form of a ball and lies partly in a seat provided therefor in the body 1 and partly in a groove 9 formed in the bearing portion 6 of the plug. The groove 9 is slightly more than a half circle in extent and is preferably arranged at a slight inclination to the minor axis of the bearing portion, thereby in co-operation 85 with the key 8 functioning as a coarse thread. As thus formed the groove 9 by its co-operation with the key 8 serves two purposes: First, at its ends it co-operates with

85 said key as a detent to limit the turning movement of the plug 4 whereby the plug may not be moved from its fully open or its fully closed position by a continuance of effort in the same direction required for the movement of the plug to fully open or fully

90 closed positions and second, it regulates the position of the plug with reference to the conforming tapering face of the bore of the body 1, compelling the close engagement of the plug with such face when the plug is turned to closed position and backing the plug slightly away from such face when the plug is turned to open position. By thus

95 preventing the movement of the plug beyond its fully open position a maximum dis- 100

105

110

charge flow of the liquid is assured and by preventing the movement of the plug beyond its fully closed position loss or waste of the liquid is avoided. By forcing the 5 plug against the conforming tapering surface of the body 1 when the plug is moved to closed position the tight closure of the plug is assured and thereby leakage is entirely prevented and by forcing the plug 10 slightly away from said conforming tapering surface when the plug is moved to open position facility of opening movement is assured, regardless of the tightness of fit between the plug and said conforming tapering 15 surface when the plug is closed. The degree to which the plug when being moved to open position is forced away from the conforming surface of the body 1 is merely sufficient to ensure ease of movement but is 20 insufficient to permit any appreciable leakage past the end of the plug when the same is opened.

By arranging the plug as an end closure for the body 1 and by wholly cutting away 25 one side of the plug to provide a discharge clearance it is possible to make the body 1 of comparatively small diameter without reducing the rate of flow of the liquid and in this way a substantial economy in manufac- 30 ture is obtained.

Where the key 8 is in the form of a ball said key may be introduced into position through an opening 15 in the wall of the body 1 and the material of said wall adjacent 35 said opening thereafter upset to provide a seat for the ball, as shown more particularly at 16, in Figure 5. Instead of using a ball as the key connection between the body 1 and the plug 4 a pin 8^a may be employed, as 40 shown in Figure 6, the pin being fitted in an opening in the body 1 flush with the outer side thereof and projecting at its inner end into the groove 9.

Referring to Figures 7, 8 and 9:

45 In this case the key connection between the body 1 and the plug 4, indicated at 8^b, is formed as an inturned extension of a split resilient ring 10 which is fitted in an annular groove 11 provided in the outer surface 50 of the body 1 adjacent the outer end thereof, the key 8^b projecting through an opening in said body into the groove 9. The construction is otherwise similar to that above described. This modified construction permits of ready removal of the plug 4 from the body 1, should such removal be found necessary or desirable. For this purpose it is

merely required to disengage the projection 8^b from the opening in the body 1 whereupon the plug 4 may be moved in the endwise direction from said body. 60

Referring to Figures 10 and 11:

In some cases to avoid loss or theft of the liquid it may be found desirable to lock the plug 4 in closed position and the modification shown in these figures is constructed with this end in view. 65

Thus the body 1 is provided at its outer end with a laterally projecting lug 12 and the plug is provided with a finger piece in 70 the form of a laterally projecting arm 7^a which is formed with an aperture 13 to receive the shackle of a pad lock 14. In the closed position of the plug as assumed by Figures 10 and 11 the opening 13 is so located with respect to the lug 12 that the shackle of a pad lock fitted in said opening will engage the lug 12 as a stop or abutment to prevent a movement of the plug to open 75 position. 80

Having fully described my invention, I claim:

A faucet comprising a body having a longitudinal bore extending the full length thereof, the rear part of said bore forming a 85 main passage which has an inlet at its rear end, and the front part having the form of an inwardly tapering conical seat which is in axial alignment with said rear part and having its large outer end flush with the 90 front end of the body, and said body having a lateral outlet port extending through said seat; an inwardly tapering conical rotary plug insertable into said seat from the front 95 end of said body and provided at its outer end with means for turning the same, and having its periphery constructed to form a solid wall and a clearance on diametrically opposite sides thereof whereby the solid wall of the plug in one rotary position of 100 the same will close said outlet port and the clearance of the plug in another position of the same will uncover said port; and means 105 for preventing complete withdrawal of said plug but causing the same to be tightened when turned into a position for closing said outlet port and loosened when the plug is turned into a position for uncovering said outlet, said means comprising a helical groove in the periphery of the plug, and an 110 internal projection in the body engaging with said groove.

HENRY D. RAHLING.
